CLAIM

The ornamental design for a display screen with transitional graphical user interface, as shown and described.

DESCRIPTION

FIG. 1 is a first image for a display screen with transitional graphical user interface;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof; and,

FIG. 12 is a twelfth image thereof.

The solid line rectangle depicts a display screen and forms part of the claimed design. The broken lines outside of the display screen show portions of environment and forms no part of the claimed design. All other broken lines within the display screen show portions of the graphical user interface and form no part of the claimed design.

The appearance of the transitional image sequentially transitions between the images shown in FIGS. 1-12. The process or period in which one image transitions to another image forms no part of the claimed design.
